[57] CLAIM

The ornamental design for a chopper with hinged receptacle, as shown and described.

DESCRIPTION

FIG. 1 is a top, front, left side perspective view of a chopper with hinged receptacle showing my new design;
FIG. 2 is a front elevational view thereof;
FIG. 3 is a left side elevational view thereof, the right side elevational view being a mirror image thereof;
FIG. 4 is a rear elevational view thereof;
FIG. 5 is a top plan view thereof;
FIG. 6 is a bottom view thereof; and,
FIG. 7 is an exploded perspective view thereof with the upper portion removed from the lower portion and shown in an open position.
